BROWN, BOVERI & CIE., OF BADEN, SWITZERLAND.

MERCURY-VAPOR RECTIFIER AND THE LIKE.

1,153,794.

Specification of Letters Patent. Patented Sept. 14, 1915.

Application filed October 1, 1914. Serial No. 864,470.

To all whom it may concern:

Be it known that I, JULIUS JONAS, a subject of the Emperor of Germany, and residing at Bruggerstrasse 22, Baden, Switzerland, have invented certain new and useful Improvements in and Relating to Mercury-Vapor Rectifiers and the like, of which the following is a specification.

This invention relates to the working of mercury vapor rectifiers and the like (it may be in parallel) by means of a common transformer.

In the accompanying drawings: Figure 1 illustrates diagrammatically a scheme of transformer winding such as is applicable to the present invention. Fig. 2 is a diagram of connections between such a transformer and two mercury rectifiers, as exemplified by the prior art. Fig. 3 illustrates diagrammatically one way of carrying the present invention into effect by means of a single phase transformer feeding two rectifiers. Fig. 4 is a similar view showing the use of a single phase transformer feeding three rectifiers and a battery, and Fig. 5 a still further view showing a polyphase transformer feeding three rectifiers.

It is a known thing to feed mercury vapor rectifiers which can work in parallel on a common direct current system, from special secondary windings of a common transformer, but it is often found in that case that the output is not uniformly distributed over the several rectifiers. The reason of this phenomenon is explained with reference to Figs. 1 and 2 which show respectively the scheme of a transformer winding and a diagram of connections between such a transformer and two mercury rectifiers.

In Fig. 1 there is represented the common single-phase transformer t , on the two cores I and II of which there are the primary windings a' , a'' and the two secondary windings b' , b'' and c' , c'' . a' is well interlinked with b' , and c' and so is a'' with b'' and c'' . Interlinking of a' with b'' and c'' , and a'' with b' and c' is not so good because the coils are wound on different core members.

If the two rectifiers g_1 and g_2 are connected up to the secondary windings of the transformer in the manner shown in Fig. 2, good working of these rectifiers is not possible. On the one hand the transformer will

show a big voltage drop (owing to great leakage) and on the other hand the distribution of the output over the two rectifiers will be unequal if in their circuits differences in themselves unimportant exist. If in fact we take into account that at any moment, of the two anodes of each rectifier, only one is conducting current, it will be perceived that of the four windings b' , b'' , c' , c'' in each moment, only two are conducting current, while the other two are without current. These windings interchange the part they play in each following half period of the alternating current. In Fig. 2 the windings b' , c' , are conducting current and only well interlinked with a' . As, however, the primary current of the transformer flows through a' and a'' in series a considerable stray flux will result owing to the bad interlinking of the secondary windings b' , c' with a'' and will entail a considerable drop of voltage in the transformer. On this scheme of connections furthermore, the secondary current may distribute itself quite differently over the windings b' and c' , because even slight differences in the rectifiers will destroy the symmetry of the parallel branches carrying current.

The object of the present invention is to provide for feeding mercury vapor rectifiers or the like from separate secondary windings of a common transformer (and where necessary working in parallel) without the above disadvantages.

The invention consists in so connecting up the anodes to the secondary windings that those parts of the secondary windings which simultaneously carry current, are in their entirety uniformly distributed over the whole primary winding.

It is to be understood that the windings of the scheme shown in Fig. 3 are disposed upon the core members in a manner similar to that illustrated in Fig. 1. These windings are connected as indicated in the diagram in Fig. 3.

In Fig. 3 the windings b' , b'' on the one hand and c' , c'' on the other are connected up to the simultaneously working anodes of the two rectifiers g_1 and g_2 so that b' and b'' simultaneously carry current during the one half period and c' and c'' during the following half period. The windings b' and b'' are well interlinked with a' and a'' as also

are c' and c'' with a' and a'' , so that the transformer shows only a very small voltage drop. Further, owing to the good interlinkage, the current in b' will stand in a fixed ratio to that in b'' determined by the number of turns on these winding parts. If, for instance, b' and b'' and c' and c'' have the same number of turns, then the currents in both rectifiers are equal. The 10 ratio of current can therefore be regulated by the ratio of the turns of these winding parts.

In Fig. 4 the primary windings a' , a'' , a''' are provided with secondary windings 15 b' , b'' , b''' and c' , c'' , c''' . Now b' is connected with c'' , b'' with c''' , b''' with c' , to form the three secondary windings, b' , c'' ; b'' , c''' and b''' , c' . These connections between the several sections of the three 20 secondaries noted are interlinked by a connecting wire which is conducted to one pole of a battery s . The free end of b' is connected with the anode e_1 , that of b'' with e_3 , that of b''' with e_6 , and the free end 25 of c'' with e_2 , that of c''' with e_4 and that of c' with e_5 . The cathodes k_1 , k_2 and k_3 are connected by a common conductor l to the other pole of the battery. As will be perceived from the direction of 30 the arrow which indicates the flow of current in one half period, the windings b' , b'' and b''' are simultaneously traversed by current and in the other half period c' , c'' and c''' .

35 In Fig. 5 the three rectifiers g_1 , g_2 and g_3 are provided with three pairs of terminals, each pair being connected with certain parts of the windings of one phase. Electrodes e_1 , e_2 are joined to b_1' and c_1'' , e_3 and e_4 are joined to b_1'' and c_1''' , e_5 and e_6 are 40 joined to b_1''' and c_1' . This completes the connections as regards one phase. As to another phase electrodes i_1 , i_2 are joined respectively to b_2' , c_2'' , i_3 and i_4 to b_2'' and c_2''' , i_5 and i_6 to b_2''' and c_2' . As to the 45 third phase the electrodes p_1 , p_2 , are connected to b_3' and c_3'' , p_3 , p_4 to b_3'' and c_3''' and p_5 and p_6 to b_3''' and c_3' .

The secondary windings connected with

the anodes of one rectifier are in star connection and the star points thus resulting are connected with each other and form the negative pole of the direct current system, the positive pole of which is represented by the connecting conductor l of the three cathodes k_1 , k_2 , k_3 . Instead of the rectifier there may also be used equivalent devices, for instance magnetically controlled stop cells according to patent application, Serial No. 854,457.

Having now described my invention, what I claim as new and desire to secure by Letters Patent is:—

1. In a system of rectification, a plurality of rectifying elements having anode and cathode circuits, a transformer supply therefor, having a plurality of sectionalized secondary windings, superposed on a primary winding, a common connection between each secondary section and each cathode circuit and connections between each secondary section and an anode circuit whereby the active anodes are fed from secondary sections, energized throughout their length by a primary portion having the same axis of magnetization.

2. A system of rectification comprising a polyphase transformer, rectifier elements provided with cathodes and anodes, corresponding in number with the polyphase supply, a plurality of sectionalized secondaries superposed on each primary phase of the transformer, common connections between each secondary section of each phase and the rectifier cathodes and connections between the other ends of the secondary sections of each phase and the rectifier anodes, whereby each active anode is fed from a secondary section energized throughout its length by a primary portion having the same axis of magnetization.

In testimony whereof, I have affixed my signature in presence of two witnesses.

JULIUS JONAS.
